DESIGN FOR A POWDER BOX

Frank McIntosh, New York, N. Y., assignor to
Lenthalic Incorporated of New York City, New
York, N. Y., a corporation of New York

Application April 21, 1933, Serial No. 47,856

Term of patent 14 years

To all whom it may concern:

Be it known that I, FRANK MCINTOSH, a citizen of the United States, residing at 25 Central Park West, New York city, have invented a new, original, and ornamental Design for a Powder Box, of which the following is a specification, reference being had to the accompanying drawing, forming a part thereof.

In the drawing:

Fig. 1 is a top plan view of a powder box showing my new design; and

Fig. 2 is a side elevation thereof.

In Fig. 1 the radial lines and in Fig. 2 the vertical white strips, the vertical black lines, and the groups of more or less parallel curved black lines, are given merely to indicate high lights, and are not a part of the design.

The dominant feature of the design consists in a light-colored top having at its rim three adjoining narrow concentric annuli, the innermost and outermost being of a lustrous metallic color and the intermediate being dark-colored and the outermost extending down the walls to form a narrow circumferential band; and dark-colored walls having at their upper border said outermost lustrous metallic narrow circumferential band and at their lower border two adjoining narrow circumferential bands, the upper being of a lustrous metallic color and the lower being dark-colored.

I claim:

The ornamental design for a powder box substantially as shown and described.

FRANK MCINTOSH.
